Primary Examiner — Brett Miller*Assistant Examiner* — Rani J Abdallah(57) **CLAIM**

The ornamental design for a bottle cap, as shown and described.

DESCRIPTION

FIG. 1 is a left, top and rear perspective view of a bottle cap showing my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown illustrate portions of the bottle cap that form no part of the claimed design.
